UNITED STATES PATENT OFFICE.

FREDERIC E. FREY, OF BUCYRUS, OHIO.

SAW-MILL DOG.

SPECIFICATION forming part of Letters Patent No. 252,451, dated January 17, 1882.

Application filed October 31, 1881. (No model.)

To all whom it may concern:

Be it known that I, FREDERIC E. FREY, a citizen of the United States of America, residing at Bucyrus, in the county of Crawford and State of Ohio, have invented certain new and useful Improvements in Saw-Mill Dogs; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention has relation to certain improvements in saw-mill dogs; and it has for its object to provide a saw-mill dog which can be graduated and secured at any height desired, and which also can be laterally adjusted and 20 secured in the timber by actuating a lever.

My invention therefore consists in a rotary shaft, having at one end an engaging-dog and at the other end a weighted lever or handle, in combination with a follower provided with extending bars and a block formed with passages 25 for the reception and passage of the bars of the follower.

My invention further consists in a shaft formed of smaller diameter near one end, and 30 provided thereon with a follower having extending bars, in combination with a slotted sliding block fitting on said bars, and provided with an eccentric-lever impinging on the extending bars.

35 My invention also consists, in a saw-mill dog, of a shaft formed with a dog at one end and a lever-handle at the other end, having an annular space between the lever-cap and shoulder of the shaft, wherein is fitted a follower having 40 lateral extending bars with a slotted sliding block provided with a double-eccentric lever acting on the extended bar, in combination with a vertical bar fitted in a slot of the sliding block.

My invention further consists, in a saw-mill 45 dog, of a horizontal shaft with a dog at one end and a weighted lever-handle at the other, and an annular space between the lever end and the shoulder on the shaft, and having a follower fitting therein, in combination with a spring 50 fixed to the follower capable of receiving and retaining the weighted handle when at rest.

My invention also consists, in a saw-mill dog, of the combination, with a saw carriage knee, of an upright standard-bar, a sliding block provided with an eccentric-lever, and a shaft provided with a follower operating in an annular space and having extended bars, as hereinafter described.

55 My invention further consists in the novel construction and combination of parts, as will be hereinafter more fully set forth and specifically claimed.

In the accompanying drawings, Figure 1 is a perspective view, showing the improvements in connection with the knee of a saw-carriage. Fig. 2 is a front view of the arched bar and its connections. Fig. 3 is a side view, showing the mode of dogging the timber; and Fig. 4 is a transverse sectional view.

Like letters refer to and identify like parts.

The letter A represents a shaft formed or provided at one end with the dog-head a, eccentrically arranged to the shaft, as shown, and from thence turned true until near the end, when it is turned of less diameter, so as to form 75 a shoulder, for the purpose hereinafter mentioned.

The letter B represents a follower, which is formed and shaped substantially as seen in Figs. 1 and 4. This follower is formed with a central circular hole fitting over the smaller part of the shaft A and abutting against the shoulder formed therein, and is provided with horizontally-extending bars b b', which are secured and fastened in the upper and lower 85 ends of the follower, and so as to admit the shaft between them, and to the outer end of the follower is secured, by any suitable means, a spring, c, which receives and retains the handle of the weighted lever C, by which the dog-head is forced into and from contact with the timber. This lever C is formed at its lower end with a strong cap-piece, d, which fits over and is firmly keyed to the end of the shaft A, with the follower set between the shoulder in 95 the shaft and the inside of the cap. On the end of this lever is a weight, e, for the purpose of giving security when the dog is set in the timber.

The letter D represents the sliding block, 100 formed with a sleeve, I, for the passage of the shaft A, the horizontal slots g for the passage

of the extending bars $b b'$, and has a vertical slot to receive the upright arm E of the bar F. This upright bar F is secured to the knee of the saw-carriage by bolts, and fits in the vertical slot of the sliding block D. This upright bar is represented in the drawings as double, and is so represented because in that shape it can be the better fastened to the ordinary knee of a saw-carriage; but the double bar is not essential, since other means may be used to effect the attachment.

The letter F' represents the double eccentric-lever pivotally attached to the sliding block, and impinging against the extending rods $b b'$ through slots in the sliding block, as seen in Fig. 2 of the drawings. The office of this lever is, when thrown back, to press upon the extending bars, and then force them against the upright bar, and by friction sustain the sliding block in any desired position, firmly secured against displacement either lateral or vertical.

The parts being arranged as set forth in the foregoing and shown in the drawings, the operation of the devices is as follows: The eccentric-lever is pulled forward, thus freeing the extending bars and uprights from the pressure and permitting the sliding block to be raised or lowered on the standard to suit the condition of the timber and the shaft to be drawn outward or pushed inward, and when adjusted to the place desired the eccentric-lever is thrown back, which secures the sliding block and shaft from displacement, and then the weighted lever is drawn down and the dog-head struck 35 into the log.

It will be observed that the handle of the eccentric-lever can be used as a hold with which to raise and lower the sliding block.

I reserve the right to vary the construction 40 and arrangement of parts without departing from the spirit of the invention herein set forth.

What I claim as my invention, and desire to secure by Letters Patent, is—

1. In a saw-mill dog, a rotary shaft con-

structed at one end with the engaging-dog eccentrically arranged to the shaft and at the other end with a weighted lever, a follower with extending bars, and a block formed with passages for the reception and passage of the bars of the follower, substantially as described. 45

2. A shaft formed at one end with a dog-head and at the other provided with a weighted lever, in combination with a follower set in a shoulder of the shaft, said follower provided with extending bars and a sliding block, substantially as described, and for the purpose set forth. 50

3. In a saw-mill dog, a horizontal shaft with a dog-head at one end and a weighted lever at the other, and provided with a follower with extending bars fixed in the annular groove formed between the shoulder on the shaft and the end of the lever-cap, in combination with spring fixed to the follower and capable of receiving and retaining the handle of the weighted 65 lever, substantially as described.

4. In a saw-mill dog, the combination, with a horizontal rotary dog-shaft provided with a lever for actuating the same, of a vertical sliding block with horizontal passages, a follower 70 with extending arms passing through said block, and a double-ended eccentric-lever bearing on said arms, substantially as and for the purpose set forth.

5. The combination, with a saw-carriage 75 knee, of an upright standard, a vertical adjustable block formed with horizontal passages, the eccentric-lever, the follower with arms extending through said passages, and a rotary dog-shaft with an actuating-lever, substantially as set forth. 80

In testimony whereof I affix my signature in presence of two witnesses.

FREDERIC E. FREY.
